(57) CLAIM

The ornamental design for a multi-opening cap as shown and described.

DESCRIPTION

FIG. 1 is a perspective view of a multi-opening cap. FIG. 2 is a front view of the multi-opening cap of FIG. 1. FIG. 3 is a rear view of the multi-opening cap of FIG. 1. FIG. 4 is a left side view of the multi-opening cap of FIG. 1. FIG. 5 is a right side view of the multi-opening cap of FIG. 1. FIG. 6 is a top view of the multi-opening cap of FIG. 1; and, FIG. 7 is a bottom view of the multi-opening cap of FIG. 1. The broken lines are shown for the purpose of illustrating parts of the article that form no part of the claimed design.

1 Claim, 4 Drawing Sheets
